UNITED STATES PATENT OFFICE.

AUGUSTIN I. AMBLER, OF WASHINGTON, DISTRICT OF COLUMBIA, ASSIGNOR
TO THE INTERNATIONAL VAPOR FUEL CARBON IRON AND MANUFAC-
TURING COMPANY, OF SAME PLACE.

GAS-GENERATOR.

SPECIFICATION forming part of Letters Patent No. 247,980, dated October 4, 1881.

Application filed February 2, 1881. (No model.)

To all whom it may concern:

Be it known that I, AUGUSTIN I. AMBLER, a citizen of the United States, residing at Washington, in the county of Washington and District of Columbia, have invented certain new and useful Improvements in Gas-Generators; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to improvements in gas-generators which are designed for producing gas from petroleum and other hydrocarbon oils, such gas being adapted for use as fuel in generating steam, heating furnaces of various kinds, and for warming buildings; and the objects of my improvements are, first, to provide a gas-generator constructed in such a form as to adapt it for use upon a locomotive-engine; second, to provide such generator with 25 a greater amount of heating-surface than has been heretofore given in the same amount of space or with the same weight of metal; third, to provide novel diaphragms for the interior portion of the generator adapted for the passage of oil, steam, and gas from one portion of the device to another. I attain these objects by the construction, combination, and arrangement of the elements of the generator illustrated in the accompanying drawings, in which—

35 Figure 1 is an elevation of my improved generator, showing pipes for the introduction of steam at different points, a pipe and branches thereof for conducting the gas from the generator, a pyrometer for showing the temperature 40 of the escaping gas, steam and gas gages for showing the pressure of the entering steam and of the escaping gas, and a glass gage for showing the height of the oil in the generator. Fig. 2 is a vertical sectional elevation, 45 showing the parts above enumerated, and in addition a pipe for admitting oil to the interior of the generator, the outer and inner cylinders, a covering of asbestos, pipes for the

admission of steam into the body of the oil within the inner cylinder and for drawing off 50 lubricating-oil and sediment, and the manner of constructing the diaphragms which divide the inner cylinder into compartments; and Fig. 3 is an elevation showing the inner cylinder and the means of admitting steam into 55 the chambers within it, and also the steam-spaces in its lower end for the passage of steam.

Similar letters refer to similar parts throughout the several views.

In constructing gas-generators of the type 60 here presented I provide a cylinder, A, of metal, of any desired dimensions, and place upon the top thereof a dome or otherwise shaped structure capable of closing its upper end, said dome or structure being riveted or 65 bolted to the cylinder in such a manner as to prevent the passage of air or other substance between the parts.

Upon the outer surface of the cylinder A and its dome there is placed a covering, A¹, of 70 asbestos or other incombustible material, which is a bad conductor of heat, and outside of this a covering, A², of wood or sheet metal, or both, for the purpose of keeping the non-conducting material in place.

75 Within the cylinder A there is secured another cylinder and dome, B, also made of metal, and of such dimensions as to leave a space, C, sufficiently broad for the circulation of steam between the two cylinders.

80 Within the interior cylinder there is placed a series of diaphragms, B², which constitute a series of chambers for the reception of steam from the space between the cylinders A and B, oblong or otherwise formed openings B' 85 being formed in the cylinder B, between said diaphragms, for its passage, they being riveted to the cylinder so as to prevent the passage at the points where they are placed of the ascending gases between them and the cylinder. 90 This construction of diaphragms or chambers provides for two heating-surfaces upon each, and thus insures the proper heating of the gas as it rises through the apertures. There may be any number of these chambers, and in 95 order that the gas generated in the apparatus

may rise freely to the dome D' in the upper portion of cylinder B, there is placed in each of the diaphragms or chambers tubular stay-bolts B³, having passages through them for the gas as it ascends. These stay-bolts also serve to strengthen the plates B² and to prevent the chambers from collapsing.

Between each of the chambers composed of the plates B² B² there is a gas-chamber, D, which insures the contact of the gas with both of said plates, and thus the vaporizing of any oil that may be carried up with the ascending gas, as well as the thorough heating of such gas.

15 Near the bottom of cylinder B there is placed a flanged plate or head, E, through which pass pipes E' E', through which steam is admitted to the body of the oil, which is placed in said cylinder for the purpose of vaporizing it. One 20 of the pipes, E', may be used for drawing off the oil after it has been reduced to the requisite gravity to be used as a lubricant.

The lower end of the cylinder B is provided with corrugations or spaces F, for the passage 25 of steam from the space between the two cylinders to the under side of the plate E.

For the purpose of admitting oil into cylinder B a pipe, G, is provided, which is to be connected to a reservoir of oil placed at a sufficient height to cause it to flow into said cylinder by its own gravity, or to a pump or other forcing device which will feed the oil. In either case the quantity allowed to enter in a given period of time is to be regulated. That 30 portion of pipe G which is within the cylinder B is provided with apertures upon its under surface for the purpose of comminuting the oil as it enters, and for distributing it over a considerable portion of the heating-surface. 35 If preferred, a rose-head may be placed upon the end of this pipe, and the distribution of the oil effected in that manner.

For the purpose of introducing steam, super-heated or otherwise, into the body of the ascending gas, a pipe, G', is used, which may be connected to any kind of a steam-superheater or to a generator, (the former being preferred,) and made to enter some distance into the interior cylinder, so as to cause the steam entering 40 to be properly commingled with the gas, and thus constitute it a hydrocarbon gas when ready for use.

In order that steam may be admitted into the space C between the cylinders A and B 45 pipes G² are placed in the outer cylinder, near its bottom, their outer ends being connected with the source of supply. The steam entering through pipes G² passes up in the space C and thence into the chambers between the flanged plates B², and is thus made to heat 50 them and to surround the interior cylinder and its dome, and thus insures the delivery of the gas at the required temperature.

Should it be found necessary to admit steam 55 to the space between the domes, it may be done by placing pipes in the apertures G³ and

connecting them with a generator of steam placed in any convenient position.

For the purpose of conducting the gas to the point where it is to be burned a T-shaped pipe 70 is inserted in the upper dome, the vertical portion of which extends down into the inner one, from which it receives the gas and conducts it to pipes H H, either or both of which may be used to conduct it to the point where it is to 75 be burned.

As a convenient method of showing the temperature of the gas or vapor as it leaves the apparatus, there is placed upon the outlet-pipe a pyrometer, I, which, by indicating the temperature thereof, enables the operator to regulate the admission of steam in such quantities as to insure the vaporization of all of the oil carried up by the ascending gas before it leaves the apparatus. I also, for convenience, place 80 a glass gage, J, upon the apparatus in any convenient position and connect it with the space occupied by the gas for the purpose of indicating the pressure thereof as it leaves the apparatus, thus enabling the operator to prevent waste at the burners by allowing too much pressure to obtain at that point. I also prefer to attach to the steam-space between the cylinders A and B a steam-gage, K, so that the pressure of steam therein may at all times be 85 90 95 known.

For the purpose of determining the height of the oil in the apparatus there is placed upon the outside thereof a glass gage, L, of the usual construction, it being made to communicate 100 with the space within the interior cylinder, one of its ends being below the oil therein and the other above it, so that the oil always rises therein to the same height that it does in the cylinder, which height may be ascertained by 105 looking at the glass tube of the gage.

Having thus described my invention, what I claim, and desire to secure by Letters Patent, is—

1. The diaphragms constituting the chambers into which steam enters from the space between the two cylinders, they consisting of flanged plates riveted to the interior cylinder and being provided with hollow stay-bolts for the passage of the ascending gases, the space 110 between them constituting a chamber into which steam enters through apertures formed in the interior cylinder between the plates, all substantially as described, and for the purpose 115 specified.

2. The interior cylinder, B, having the corrugations or spaces F at its lower end for the passage of steam and a series of perforated diaphragms or steam-chambers arranged within it, substantially as and for the purpose set 120 forth.

3. The combination, in a gas-generator, of an outer cylinder having a dome upon its upper end and an interior cylinder of similar construction for containing the oil to be vaporized, 125 having in it a series of perforated diaphragms which constitute chambers, which are supplied

with passages communicating with the space between said cylinders for the passage of steam therefrom, whereby the heating-surface is largely increased, substantially as set forth.

5. 4. The combination of the plate E, pipes E', and steam-passages F, whereby steam is admitted to the body of the oil in the interior cylinder and beneath the lower chamber there-

of, substantially as and for the purpose set forth.

In testimony whereof I affix my signature in presence of two witnesses.

AUGUSTIN J. AMBLER.
